To all whom it may concern:

Be it known that I, Roy G. Fig. 1 is a front view of an elastic braid embodying my new design, to which no tension is applied;

Fig. 2 is a side view of the elastic braid shown in Fig. 1;

Fig. 3 is a rear view of the elastic braid shown in Fig. 1; and

Fig. 4 is a view of the elastic braid of Fig. 1, as it appears when subjected to substantially maximum stretch.

The figures disclose the elastic braid enlarged to approximately three times normal size so that it will appear approximately double size upon reduction of the same to the ultimate size as appearing in the patent copy.

The ornamental design for an elastic braid, as shown and described.
